UNITED STATES PATENT OFFICE.

GEORGE H. SMITH, OF NUTLEY, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

1,034,154.

Specification of Letters Patent. Patented July 30, 1912.

Application filed February 25, 1909. Serial No. 479,859.

To all whom it may concern:

Be it known that I, GEORGE H. SMITH, citizen of the United States, and resident of Nutley, in the county of Essex and State of New Jersey, have invented certain new and useful Improvements in Type-Writing Machines, of which the following is a specification.

My invention relates to typewriting machines and more particularly to the type actions of such machines.

The main objects of my invention are to provide an efficient and easy acting type action and one in which the parts are so constructed and arranged that the type basket may be shifted to change the "case" position of the type bars.

To the above and other ends which will hereinafter appear, my invention consists in the features of construction, arrangements of parts and combinations of devices to be hereinafter described and claimed.

In the accompanying drawings in which like reference characters designate corresponding parts in the various views, Figure 1 is a central, vertical fore and aft sectional view showing sufficient of one form of typewriting machine to illustrate my invention in its embodiment therein. Fig. 2 is a vertical transverse sectional view of the same, taken on a line $x-x$ of Fig. 1 and looking in the direction of the arrows at said line. Fig. 3 is a skeletonized view corresponding to Fig. 1 but showing the type basket shifted for upper case writing. Fig. 4 is a detail perspective view of the fixed auxiliary frame. Fig. 5 is a detail perspective view of the shiftable frame which carries the type bars and certain of the actuating parts. Fig. 6 is a detail perspective view of the rocking member by which the type basket is shifted.

The frame of the machine comprises a base 1, corner posts 2 and a top plate 3. A carriage (not shown) of suitable construction is mounted upon the top plate of the machine in the usual, or any preferred, manner to travel from side to side thereof under control of escapement mechanism, the carriage carrying a cylindrical platen 4, diagrammatically shown in Figs. 1, 2 and 3. Key levers 5 are provided with finger keys 6 and are fulcrumed on a fulcrum bar 7 secured to the base of the machine by screws 8. Each key lever is connected to one end

of a contractile restoring spring 9 which is connected at its opposite end to a hook-like member 10 forming part of a plate 11 secured to the base of the machine by screws 12. Upwardly extending links 13 are each pivoted at one end as at 14 to a key lever 5 and at its opposite end to a forwardly extending arm of an angular sub-lever 15 pivoted at 16 to a hanger 17 secured by screws 18 to a segment 19. From an inspection of Figs. 1 and 2 it will be seen that the hangers 17 are all vertically disposed and are segmentally arranged and that the angular levers 15 are at progressively higher elevations from the center to the sides of the system. The upright arm of each angular lever is pivoted at 20 to a forwardly extending link 21 which in turn is pivoted at 22 to a sub-lever 23 intermediate the ends of the latter. Each sub-lever is pivoted at its forward end as at 24 to a hanger 25 secured by screws 26 to a segment 27. The hangers 25 are bifurcated to receive the sub-levers and extend rearwardly from their supporting segment, whereas the hangers 17 are bifurcated to receive the angular levers 15 and extend forwardly from their supporting segment 19. The rear end of each sub-lever 23 is pivoted at 28 to a link 29 which in turn is pivoted at 30 to the heel 85 of a type bar 31. From an inspection of the drawings it will be seen that each sub-lever 23 is arranged longitudinally fore and aft of the machine and extends in the same general direction as the companion link 29 to 90 which it is pivoted, each link 29 and its companion lever 23 being arranged end to end. The hangers 25, as will be seen from an inspection of Fig. 2, are all vertically disposed and are segmentally arranged. The 95 segmental arrangement of the hangers 25 corresponds substantially to the segmental arrangement of the hangers 17 so that the hangers 25 are at progressively greater elevations from the center to the sides of the 100 system.

The type bars are segmentally arranged to strike upwardly and rearwardly against the front face of the platen and are arranged in two groups, one group being pivoted at 32 to radially disposed segmentally arranged hangers 33, and the other group being pivoted at 34 to a set of hangers 35 having a like disposition but being arranged at a higher elevation than the hangers 33. The 110

type bar hangers of both sets are preferably substantially U-shaped as indicated in Fig. 2. The type bars of both groups extend forwardly to essentially the same transverse plane in a basket by reason of the 45° arrangement of the pivots 32 and 34 of the two groups of type bars, the ends of the type bars being supported upon a pad 36 which in turn is supported in a trough-like member 37 which constitutes a part of the segment 27. The segment 27 is connected by bars 38 to the type bar segment 39 as shown in detail in Fig. 5 so that the segments 27 and 39 constitute a frame which may be shifted together with the parts which are carried thereby. Thus parallel guide links 40 are pivoted at their forward ends as at 41 upon shouldered pivot screws which pivotally connect the links to the type bar segment. The rear ends of the links are pivoted by shouldered pivot screws 42 to upwardly extending arms 43 that constitute part of a fixed auxiliary frame shown in detail in Fig. 4 and which is detachably fixed in the main frame of the machine. A rock shaft 44, shown in detail in Fig. 6, is mounted at its ends on pivot screws 45 which are received in threaded openings in the bosses 46 of the fixed auxiliary frame 30 and extend inwardly from the outer sides thereof. This rock shaft is provided with forwardly extending integral arms 47 connected by shouldered pivot screws 48 to the type bar segment or shiftable frame. The parallel arms 47 together with the parallel links 40 constitute parallel motion members upon which the shiftable frame together with the parts carried thereby may be shifted to change the case position of the type bars relatively to the platen. From an inspection of Figs. 1 and 4 it will be seen that the segment 19 hereinbefore described is connected by screws 49 to upwardly extending lugs 50 formed on the auxiliary frame 45 so that the segment 19 and hangers 17 are supported by a fixed portion of the machine. The fixed auxiliary frame carries forwardly extending lugs 51 tapped to receive screws 52 which extend in opposite directions and 50 the inner ends of which constitute stops with which the outwardly projecting ends 53 of the shouldered screws 48 coöperate, it being understood that the ends 53 of said screws project beyond the sides of the segment 39 and between the coöoperative stops 52 in order to limit the shifting movements of the shiftable frame. Contractile springs 54 are arranged upon opposite sides of the machine, one end of each spring having its 55 convolutes surrounding an exteriorly threaded member 55 that is tapped to receive a headed screw 56 which extends through an opening in the top plate of the machine, the head 57 of the screw being supported upon 60 the top plate. By this arrangement a turn-

ing of the screws 56 adjusts the pressure applied by the springs. The lower end of each spring is connected to an apertured lug 58 on one of the arms 47. The power of the springs 54 is thus exerted to normally 70 maintain the shiftable frame in its elevated position where the lower case type 59 on each type bar is adapted to co-act with the platen as indicated in Fig. 1. Each arm 47 has a depending lug 60 thereon to which a 75 link 61 is pivoted. The lower end of each link is pivoted to a shift lever 62 provided with a finger key 63 in the keyboard of the machine and at each side of the keyboard. By reason of the rigid connection between 80 the arms 47 an actuation of either of the shift keys is effective to move the shiftable frame downwardly against the pressure of the springs 54, as indicated in Fig. 3, in order that the upper case type 64 of each 85 type bar may be positioned so as to be brought to the printing point when the type bar is actuated. It will be observed that in shifting the type basket from the position shown in Fig. 1 to that indicated in Fig. 3 90 that the type bars, the links 29, levers 23 and forward ends of the links 21 move together, whereas the angular levers, links 13, and key levers remain at rest. During this shifting movement of the parts the forward 95 ends of the links 21 receive a shifting movement with the type basket, the links turning on the pivots 20 which connect them to the angular levers.

The construction is such that the sets of 100 links 29, levers 23 and links 21 each have a segmental arrangement that corresponds substantially to the segmental arrangement of the system of type bars, and the hangers 25, 17 and angular levers 15 also have a 105 corresponding arrangement so that as the sides of the system of type bars are approached the actuating members and the parts that carry them are at gradually increasing elevations which correspond substantially to the increasing elevations at which the type bars are mounted. The links 13 gradually increase in length from the center to the sides of the system, as indicated in Fig. 2, in order to compensate for 110 the difference in the elevation of the angular levers 15 as the sides of the system are approached.

The construction of each type action is such that an easy start may be effected at 120 the initial portion of the stroke and the movement of the type bar is accelerated as it approaches the printing point. A depression of a finger key 6 effects a turning movement of the corresponding angular 125 lever 15 which is effective to produce a forward longitudinal movement on the companion link 21. This in turn effects a forward movement of the associate lever 23 around its pivot 24 which produces a pull 130

on the coöperating link 29, thus throwing the associated type bar to the printing point. The construction is such that the movement of each lever 23 is in the general direction of the movement of the type bar as it leaves its normal position so that ample room is provided for the actuation of the parts. Moreover, it will be understood from an inspection of Fig. 2 that the system of key levers is substantially co-extensive with the system of type bars and the system of intermediate connections between the type bars and key levers, and that the points of connection between the intermediate actuating devices of each type bar and its associated key lever are in the same plane so that there is no side strain on the parts, and that the type bar swings to the printing point by a pull upon the associated link 29 which is fore and aft of the machine. This construction provides an easy action devoid of lateral or side strains and one which is easy at the start and gradually accelerates the movement of the bar as it approaches the printing position. This last may be appreciated by a comparison of the positions of the type at *a b c* and *d* in Fig. 1 with the positions of the key head at the corresponding points in its depression. Each of the links 13, 21 and 29 is preferably made of a two-part link detachably connected to the parts with which it is associated. By the two-part construction of the links 29, for instance, each link at a side of the machine may have its rear end turned at one angle to co-act with the radially disposed type bar and may have its forward end connected to the associated actuating lever which moves in a vertical plane. The two-part links may thus readily accommodate themselves to the different angular positions of the parts to which they are connected.

What I claim as new and desire to secure by Letters Patent, is:

1. In a typewriting machine, the combination of a shiftable type bar segment, type bars carried thereby, a link connected to each type bar, a lever arranged longitudinally of each link and pivoted thereto, said links and levers partaking of the shifting movements of the segment, keys, and intermediate connections between said keys and levers that permit the shifting of the levers with the segment.
2. In a typewriting machine, the combination of a shiftable type bar segment, type bars carried thereby, a link connected to each type bar, a lever arranged longitudinally of each link and pivoted thereto, said links and levers partaking of the shifting movements of the segment, key actuated sub-levers, and links between said first mentioned levers and said sub-levers.
3. In a typewriting machine, the combination of a shiftable type bar segment, type bars carried thereby, a link connected to each type bar, a lever arranged longitudinally of each link and pivoted thereto, said links and levers partaking of the shifting movements of the segment, key actuated sub-levers, and links between said first mentioned levers and said sub-levers.

nation of a shiftable type bar segment, type bars carried thereby, a link connected to each type bar, a lever arranged longitudinally of each link and pivoted thereto, said links and levers partaking of the shifting movements of the segment, key actuated sub-levers carried by a fixed portion of the machine, links intermediate said first mentioned levers and sub-levers, and which swing around their points of connection with the sub-levers when the segment is shifted.

4. In a typewriting machine, the combination of a shiftable type bar segment, type bars carried thereby, a link connected to each type bar, a lever arranged longitudinally of each link and pivoted thereto, said links and levers partaking of the shifting movements of the segment, angular sub-levers carried by a fixed part of the machine, links intermediate said first mentioned levers and said angular levers, key levers, and links intermediate said key levers and angular levers.

5. In a typewriting machine, the combination of a shiftable type bar segment, type bars carried thereby, a link connected to each type bar, a lever arranged longitudinally of each link and having one end pivoted to the link and fulcrumed at the other end, said links and levers partaking of the shifting movements of the segment, keys, and intermediate connections between said keys and levers that permit the shifting of the levers with the segment, said connections connecting with the levers intermediate the ends of the latter.

6. In a typewriting machine, the combination of a shiftable type bar segment, type bars carried thereby, a link connected to each type bar, a lever arranged longitudinally of each link and pivoted thereto, said links and levers partaking of the shifting movements of the segment, key actuated sub-levers carried by a fixed portion of the machine, and links each connected to one of said first mentioned levers intermediate its ends and also connected to one of said sub-levers, which last mentioned links swing around their points of connection with the sub-levers when the segment is shifted.

7. In a front-strike typewriting machine, the combination of a series of upwardly and rearwardly striking type bars, a shiftable segment carrying said type bars, actuating pull links which extend longitudinally fore and aft of the machine beneath the type bars and which are connected directly to the type bars, actuating levers which extend longitudinally fore and aft of the machine beneath the type bars and which are connected to said links, and a second set of key actuated actuating links which extend longitudinally fore and aft of the machine beneath the type bars and which are connected directly to said levers.

8. In a front-strike typewriting machine, the combination of a series of upwardly and rearwardly striking type bars, a shiftable segment carrying said type bars, actuating pull links which extend longitudinally fore and aft of the machine beneath said type bars and which are connected directly to the type bars, actuating levers which extend longitudinally fore and aft of the machine beneath the type bars and which are connected to said links, and a second set of key actuated actuating links which extend longitudinally fore and aft of the machine beneath the type bars and which are connected directly to said links, the first mentioned links and said levers shifting with the segment and one end of each of the second set of links swinging around a pivot when the segment is shifted.
- 10 9. In a front-strike typewriting machine, the combination of a series of upwardly and rearwardly striking type bars, a shiftable segment carrying said type bars, actuating pull links which extend longitudinally fore and aft of the machine beneath said type bars and which are connected directly to the type bars, actuating levers which extend longitudinally fore and aft of the machine beneath the type bars and which are connected directly to said links, a second set of actuating links which extend longitudinally fore and aft of the machine beneath the type bars and which are connected directly to said levers, and a second set of key-actuated levers to which said last mentioned actuating links are directly connected.
- 15 10. In a front-strike typewriting machine, the combination of a series of upwardly and rearwardly striking type bars, a shiftable segment carrying said type bars, links which extend longitudinally fore and aft of the machine and which are connected to the type bars, levers which extend longitudinally fore and aft of the machine and which are connected to said links, a second set of links which extend longitudinally fore and aft of the machine and which are connected to said levers, a set of angular sub-levers to which said last mentioned links are connected, key levers, and links intermediate the key-levers and angular sub-levers.
- 20 11. In a front-strike typewriting machine, the combination of a series of upwardly and rearwardly striking segmentally arranged type bars, a shiftable segment carrying said type bars, segmentally arranged links which extend longitudinally fore and aft of the machine and which are connected to the type bars, segmentally arranged levers which extend longitudinally fore and aft of the machine and which are connected to said links, the segmental arrangement of said links and levers corresponding substantially to the segmental arrangement of the type bars, and a second
- 25 set of key actuated links which extend longitudinally fore and aft of the machine and which are connected to said levers.
- 30 12. In a front-strike typewriting machine, the combination of a series of upwardly and rearwardly striking segmentally arranged type bars, a shiftable segment carrying said type bars, segmentally arranged links which extend longitudinally fore and aft of the machine and which are connected to the type bars, segmentally arranged levers which extend longitudinally fore and aft of the machine and which are connected to said links, a second set of segmentally arranged key actuated links which extend longitudinally fore and aft of the machine and which are connected to said levers, the segmental arrangement of both sets of links and of said levers corresponding substantially to the segmental arrangement of the type bars.
- 35 13. In a front-strike typewriting machine, the combination of a series of upwardly and rearwardly striking type bars, actuating pull links arranged beneath said type bars and connected directly to the type bars, actuating levers arranged beneath the type bars and connected directly to said links, a shiftable frame which carries said type bars, actuating links and levers, a second set of levers fulcrumed on a fixed part of the machine beneath the type bars, and actuating links arranged beneath the type bars and connecting the two sets of levers, said last mentioned links permitting the shifting of the shiftable frame and the parts carried thereby independently of the second set of levers.
- 40 14. In a front-strike typewriting machine, the combination of a series of upwardly and rearwardly striking type bars, links that extend longitudinally fore and aft of the machine, levers extending longitudinally fore and aft of the machine, each of said levers being fulcrumed at one end and connected at its opposite end to one of said links, a shiftable frame which carries said type bars links and levers, a set of sub-levers pivoted to a fixed part of the machine and a second set of links connecting said first mentioned levers and said sub-levers, the last mentioned links extending fore and aft of the machine.
- 45 15. In a front-strike typewriting machine, the combination of a series of upwardly and rearwardly striking type bars, links that extend longitudinally fore and aft of the machine, a set of levers extending longitudinally fore and aft of the machine, each of said levers being fulcrumed at one end and connected at its opposite end to one of said links, a shiftable frame which carries said type bars links and levers, a set of angular sub-levers of a substantially uniform size pivoted to a fixed part of the ma-

chine, a second set of links connecting said first mentioned levers and said angular sub-levers, the last mentioned links extending fore and aft of the machine, key levers, 5 links intermediate said key levers and angular sub-levers, and keys for actuating said key-levers.

16. In a front-strike typewriting machine, the combination of a series of segmentally arranged upwardly and rearwardly striking type bars, segmentally arranged links that extend longitudinally fore and aft of the machine, a set of segmentally arranged levers extending longitudinally 10 fore and aft of the machine, each of said levers being fulcrumed at one end and connected at its opposite end to one of said links, a shiftable frame which carries said type bars links and levers, a set of segmen-

tally arranged angular sub-levers of a substantially uniform size pivoted to a fixed part of the mach'n', a second set of segmentally arranged links connecting said first mentioned levers and said angular sub-levers and connected with the first mentioned levers intermediate their ends, the last mentioned links being segmentally arranged and extending fore and aft of the machine, key levers, and links intermediate 15 said key levers and angular sub-levers. 20

Signed at the borough of Manhattan, city of New York, in the county of New York and State of New York, this 23rd day of February, A. D. 1909.

GEORGE H. SMITH.
